CLAIM

The ornamental design for a receptacle for bicycle lock, as shown and described.

DESCRIPTION

FIG. 1 is a front perspective view of a receptacle for bicycle lock showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines represent portions of the receptacle for bicycle lock that form no part of the claim.

1 Claim, 5 Drawing Sheets(56)
